SAMUEL H. DOLBEAR, OF SAN FRANCISCO, CALIFORNIA, ASSIGNOR TO PNEUMATIC PROCESS FLOTATION COMPANY, OF NEW YORK, N. Y., A CORPORATION OF DELAWARE.

METHOD OF CONCENTRATING ORES.

Application filed December 15, 1920. Serial No. 431,024.

To all whom it may concern:

Be it known that I, SAMUEL H. DOLBEAR, a citizen of the United States, residing at San Francisco, in the county of San Francisco and State of California, have invented new and useful Improvements in Methods of Concentrating Ores, of which the following is a specification.

This invention relates to the concentration of ores and has for its object the provision of an improved method of ore concentration.

The method of the present invention, while not a flotation process in the sense in which that process is understood in the art, partakes of the nature of the flotation processes of ore concentration in that it takes advantage of the well known preference of a froth containing certain substances of the class designated in the art as "flotative agents" for certain mineral and metallic substances such as metallic sulfides present in ore and its equivalents. The concentration of ores by flotation is now commonly practiced by either the agitation froth process or the pneumatic flotation process. In the agitation froth process, the ore pulp, consisting of the finely divided ore mixed with from 3 to 5 times its weight of water, together with a small quantity of an appropriate flotative agent is mechanically agitated until the metalliferous matter forms into a froth which is separated from the remainder of the ore pulp. In the pneumatic flotation process, the ore pulp together with a flotative agent is subjected to aeration of such a character that a body of froth is formed and continuously maintained above the body of ore pulp, and mineral particles in the ore pulp are elevated into this body of froth by the levitating action of the air bubbles rising through the body of the ore pulp, and are subsequently recovered from the froth. In each of these flotation processes, the ore pulp together with an appropriate flotative agent is itself directly acted upon by a physical force, this force being in one case mechanical and in the other case pneumatic.

My present invention contemplates the concentration of ores by creating or producing a froth having a selective retentive affinity for certain components of the ore, or a froth of such character that the gangue settles more rapidly than the metalliferous matter present in the ore when the latter is fed into or upon such body of active froth above the lower boundary thereof. Thus, the method of the present invention involves the production of a body of froth having a selective retentive affinity for certain components of the ore, and the introduction of ore directly into this body of froth from a source independent of and out of contact with the froth forming means and under conditions such that the metalliferous matter in the ore is more readily retained by the froth than is the gangue matter in the ore. In carrying out the method of the invention, any suitable amount of oily liquid or other appropriate flotation agent is used and a small amount of acid or alkali may be used alone or in addition thereto, as may be determined necessary or desirable by simple tests now known to all skilled in the art of flotation. The method of the invention is not, however, a flotation process, in that the ore is not agitated nor is a mixture of the ore, water and flotative agent mechanically agitated or aerated as in the well known agitation froth and pneumatic flotation processes.

In the practice of the present invention, in its preferred form, I first produce or create a froth having a selective retentive affinity for certain components of an ore by agitating and/or aerating a liquid containing an appropriate frothing agent generally a flotative oil to which may be added, if desired, other reagents such as acid or alkali. Thereafter pulverized ore is introduced into this froth at a point above the lower level of the froth. Any suitable means may be employed for evenly depositing the ore upon or in the froth. The metalliferous particles present in the ore having a preference for the froth containing oil or other flotative agent become attached to the froth and are thereby retarded or prevented from sinking,

whereas the gangue or earthy substances present in the ore sink with greater rapidity and thus become separated from the metalliferous particles. The froth containing the 5 metalliferous particles is thereafter removed and the gangue suitably disposed of.

It is well known that one mineral or metallic substance may have a greater preference for a froth containing a given flotation 10 agent than another mineral or metallic substance. Advantage may be taken of this phenomenon in the treatment of mixed ores, such as ores containing mixed sulfides, in accordance with the method of the present 15 invention with the view of differentially separating the different metalliferous substance, the metalliferous substance having the greater preference for the froth and its flotation agent being retained in the upper 20 part of the froth which is separated from that in the lower part; or the ore may be treated two or more times by the process of the invention in order first to collect the metalliferous matter most readily retained 25 in the froth, allowing the metalliferous matter less readily retained to sink in the froth and be subsequently retreated by the same or some other suitable method.

If a finely divided mixed sulfide ore is 30 introduced into a selective froth in accordance with the present invention the different metalliferous substances in the ore will sink into the froth to a distance approximately proportional to their relative affinities for the selective froth. In other words, the metalliferous substances will tend to distribute themselves throughout the froth in a gradient manner, that metalliferous substance having the greatest preference 35 for the froth remaining near the top and that metalliferous substance having the least preference for the froth sinking to or near the bottom of the froth. It will therefore be evident to those skilled in 40 the art that in practicing the present invention with a mixed ore, such as a mixed sulfide ore, the body of froth may be divided into layers or zones, each layer or zone containing a preponderating amount of 45 metalliferous matter of a particular composition or character, and the metalliferous matter in these different zones may be separately removed and collected.

The froth employed in the practice of the 50 present invention may be produced by mechanical agitation of a flotation agent with a suitable liquid, such as water, together with other reagents, if necessary or desirable, and the pulverulent ore fed into or 55 upon such froth while it still resides upon such liquid. A froth having a selective retentive affinity for certain components of an ore may also be obtained by aerating a liquid containing an appropriate frothing 60 and/or flotation agent. The froth em-

ployed in the practice of the invention is an unstable froth which is continuously breaking down and continuously being replaced by fresh froth.

The ore introduced into or upon the body 70 of active froth is finely divided, that is, reduced to a floatable size, and may be either wet or dry, and may be treated in any desired manner, such as with an oily liquid, acid or other reagent. 75

The method of the present invention has a number of advantages over the flotation processes now in use, all of which latter require that the ore be kept in constant agitation or motion while in the flotation 80 apparatus in order to secure contact with the flotation agent or with gas bubbles, and even then some of the mineral particles avoid such contact and thereby become lost to flotation. In the method of the present invention, the contact is easily made positive by feeding the ore in a finely divided condition directly into the body of froth and from a source independent of and out 85 of contact with the froth forming body of liquid. In the customary flotation processes, it is necessary to supply sufficient power to keep the ore in constant motion or agitation while in the flotation apparatus, so that each ton of ore so treated requires the 90 expenditure of a certain amount of power for this purpose. In the process of the present invention, the ore itself is not agitated, hence a substantial saving in power 95 results. 100

In the practice of the present invention, it may be desirable to feed the ore to the froth near one end of the cell or vessel, and to keep the froth traveling toward the other end of the vessel where it is discharged. 105 This gives the gangue and earthy materials time to sink through the froth and to become separated from mineral or metallic particles which are retained in the froth.

In the accompanying drawings, 110

Fig. 1 is a sectional elevation of an apparatus, particularly adapted for the practice of the present invention;

Fig. 2 is perspective view of a portion 115 of the apparatus; and

Fig. 3 is a partial sectional elevation of a slightly modified form of apparatus adapted for the practice of the invention.

Figures 1 and 2 of the accompanying 120 drawing illustrate an apparatus particularly adapted for the practice of the present invention. This apparatus comprises a tank 10 having a transverse porous medium 11 arranged near the bottom thereof. The porous medium may be of any appropriate 125 character, such as canvas, porous tile, or the like, which is adapted to support a suitable body of liquid and at the same time permit the passage upwardly therethrough of an appropriate quantity of a suitable 130

gas, such, for example, as air. A plurality of gas compartments 12 are provided beneath the porous bottom 11, and an appropriate gas, such as air, under suitable pressure, is admitted to the compartments 12 by means of valved pipes 13 communicating with a gas supply main 14.

The liquid level in the tank 10, under normal operating conditions, is not higher than the line *a*. Liquid, such as water, and appropriate frothing and/or selective agent or agents are introduced into the tank 10 through a pipe 15 provided at its upper end with a funnel 16. The tank 10 is also provided with a liquid discharge pipe 17, the valve of which, under normal operating conditions, is maintained closed.

A plurality of V-shaped deflectors or troughs 18 are mounted in the upper portion of the tank 10 above the normal liquid level of the tank under operating conditions. The deflectors are arranged transversely in the tank and are parallel to one another. Each deflector is provided with substantially horizontal flanges 19 and the deflectors are arranged so that the flanges 19 of adjacent deflectors overlap. The overlapping flanges 19 are appropriately spaced so as to permit the passage therebetween of froth formed above the liquid level *a*.

A perforated hollow drum 20 is provided for feeding ore or ore pulp into or upon the body of froth formed above the deflectors 18. The drum is mounted for rotation upon rollers 24. The perforations of the drum are preferably staggered in order to uniformly distribute the ore and to avoid channelling and breaking down of the froth. A stationary feed pipe 21 having a discharge opening or openings 22 is mounted centrally within the drum 20. The drum is interiorly provided with a plurality of spaced baffles 23.

The troughs 18 project through one side wall of the tank 10 and are arranged to discharge into launders 25 mounted on the side of the tank. One or more launders may be provided for collecting the discharge from troughs 18, and in the apparatus illustrated in the drawing three such launders are provided.

The practice of the present invention in the apparatus illustrated in the accompanying drawing is substantially as follows: Air, or other suitable gas, is forced through the porous medium 11 into the liquid in the tank 10 and forms within this liquid a continuously rising stream of air or gas bubbles. The liquid level is maintained approximately constant by adding additional liquid, such as water, to the tank through the supply pipe 15. An appropriate flotation and/or selective agent or agents are supplied to the liquid in the tank through the pipe 13. In some in-

stances, it is advisable to emulsify the flotation and/or selective agent before introducing it into the tank, since the free agent might tend to kill the froth. Froth-making gas bubbles rise to the surface of the liquid and there is formed above such surface a body of froth which gradually rises and coming in contact with the deflectors 18 is forced through the apertures between the overlapping flanges 19. In this manner a mass of froth is built up reaching in depth or thickness from the top of the liquid level (*a*) to or above the level of the upper froth discharge 26.

When a suitable depth of froth has been formed, ore or ore pulp of appropriate consistency is conducted into the drum 20 through the feed pipe 21 and discharged into the drum through the apertures 22. The lower portion of the drum preferably comes in contact with the froth since it is desirable to prevent the ore from falling upon the froth, thereby causing the froth to be broken down. The ore, upon discharging from the apertures 22, strikes the baffles 23, the weight of the falling ore being sufficient to revolve the drum 20, the drum being supported by the rollers 24 upon which it revolves. The speed of rotation of the drum may be appropriately varied by adjusting the spouting velocity of the ore discharged from the feed tube 21. The ore passes through the perforations of the drum into the body of froth in the tank 10. The froth rising through the apertures between the overlapping flanges 19 immediately below the drum receives a charge of ore Gangue matter, having no preference for the selective agent in the froth, sinks out of or into the lower portion of the froth, and is caught in the V-shaped troughs or deflectors 18, and is discharged through the wall of the tank into the launders 25. From the launders 25 such gangue matter may be conducted to any suitable place for disposal or retreatment.

Mineral particles exhibit a tendency to remain in the froth while gangue particles exhibit a tendency to fall through the froth and for these reasons the froth and more particularly the top portion thereof becomes enriched in metalliferous matter. The entire body of froth is given a longitudinal movement, that is, a movement from the feed end of the apparatus towards the discharge end. In other words, as viewed in the drawing, the body of froth moves from left to right, and is discharged into launders 28 and 29 through discharge openings 26 and 27 respectively. This movement of the froth is due to the fact that the froth is ejected through the spaces or apertures between the flanges 19 with a lateral movement, and such lateral movement is imparted to the overlaying froth. If de-

sired, the discharge opening 27 may be closed. When open, this discharge opening enables the froth to be removed at two different levels thereby obtaining concentrates of different grades or of different characters.

If desired, the apparatus may be operated so as to permit certain of the mineral particles to sink out of the body of froth altogether, and to pass into the V-shaped troughs 18, and to be there collected as concentrates. The gangue will, of course, be first deposited in the troughs 18 nearest the feed end of the apparatus and would, in such cases, be disposed of by the first launder 25 separately from the product or products deposited in the V-shaped troughs near the discharge end of the apparatus. Several different products may, if desired, be collected in this way. Thus, three different products can be collected from the three launders 25 and two additional different products can be collected in the launders 28 and 29. In this manner, it is practicable to carry out with ease various procedures of differential separation or concentration of ores.

Fig. 3 illustrates the method of practicing the invention in an apparatus wherein the froth is produced by agitation. An agitation chamber 11' communicates by means of an opening 12' with the tank 10' which is in all essentials identical to the tank 10 shown in Fig. 1. A shaft 13' adapted for rotation is suspended within the agitation chamber 11' and carries at its lower end agitation blades 14'. Liquid, such as water and appropriate frothing and/or selective agent or agents are introduced into the agitation chamber 11' through a pipe 15' provided at its upper end with a funnel 16'.

After an appropriate quantity of liquid, such as water, containing a flotation agent or agents has been introduced into the agitation chamber 11', the shaft 13' carrying the agitation blades 14' is rapidly rotated thereby violently agitating the liquid contained in the agitation chamber 11' and incorporating a quantity of air with the liquid. The liquid thus incorporated with air passes into the tank 10' through the opening 12' where the air rises to the surface of the liquid in the form of a froth. A number of agitation chambers may be placed along the sides of the tank 10' thereby assuring a uniform formation of froth throughout the entire length of the tank 10'.

It will be readily understood by those skilled in the art of flotation metallurgy that many of the developments in flotation may be easily used in the practice of the present invention. It is not believed to be necessary to further cite specific directions as to other types of apparatus suitable for

producing an appropriate froth nor for separating the mineral bearing froth from the gangue, nor to describe in detail the many oils or floatative agents and other reagents which may be used in the practice of the present invention.

I claim:

1. The method of concentrating ores which comprises distributing pulverized ore evenly and without agitation directly into contact with a substantially non-agitated body of froth having a selective retentive affinity for certain components of the ore, permitting other components to sink through the froth, and separating the components retained by the froth. 75

2. The method of concentrating ores which comprises producing a froth having a selective retentive affinity for certain components of the ore, distributing ore into the froth at a point above the lower boundary of the froth, permitting certain components of the ore to sink through the froth, and separating the components retained by the froth. 85

3. The method of concentrating ores which comprises aerating a liquid containing a frothing agent to produce a froth having a selective retentive affinity for certain components of the ore, distributing ore into the froth at a point above the lower boundary of the froth, permitting certain components of the ore to sink through the froth, and separating the components retained by the froth. 95

4. The method of concentrating ores which comprises producing above the surface of a liquid containing a frothing agent a froth having a selective retentive affinity for certain components of the ore, distributing ore directly into said froth from a source independent of and out of contact with said liquid and under such conditions that certain components of the ore are more readily retained by the froth than other components of the ore, and recovering the components more readily retained by the froth by froth overflow. 105

5. The method of concentrating ores which comprises aerating a liquid containing a frothing agent to form above the liquid a froth having a selective retentive affinity for the metalliferous matter in an ore, distributing ore directly into said froth from a source independent of and out of contact with said liquid and under conditions such that the metalliferous matter in the ore is more readily retained by the froth than is the gangue matter in the ore, and recovering metalliferous matter from the froth by froth overflow. 115

6. The method of concentrating ores containing different metalliferous substances which comprises producing a body of froth having a selective retentive affinity for the 120

metalliferous matter in the ore, distributing the ore directly into the froth at a point above the lower boundary of the froth whereby the metalliferous matter in the ore is more readily retained in the froth than is the gangue matter in the ore, permitting the different metalliferous substances present in the ore to arrange themselves in the froth in zones in each of which a particular metalliferous substance predominates, and 10 separately recovering the metalliferous substance in the different zones of the froth.

SAMUEL H. DOLBEAR.
